CANOPY FRAME

Matilda D. Welsh, Ladue, Mo.

Application March 22, 1946, Serial No. 656,259

4 Claims. (Cl. 135—7.1)

1

This invention relates to a canopy frame and concerns itself more particularly with a collapsible frame for a baby carriage canopy.

It is an object of the invention to provide a canopy frame which may be positively locked in its erected position and which may be folded from its erected position through the operation of two levers.

Another object of the invention is to provide a collapsible mechanism for a canopy frame by means of which the same may be locked in its erected position and collapsed from this position through the operation of the mechanism's locking levers.

More specifically it is an object of the invention to provide a collapsible canopy frame having a main bow and a shield bow supported thereon through a triangular shaped linkage, one leg of which mounts a plurality of supporting bows or ribs and the other leg of which comprises a series of linkages manipulable by two operating levers in one instance to lock the collapsible frame in an erected position and in another instance to collapse the same into a folded position.

A still further object of the invention is to provide a collapsible canopy frame having a main bow which supports a forwardly disposed shield bow from which a sun visor bow may be lowered to depend from said shield bow.

Yet another object of the invention is to provide a canopy frame having improved corner brackets for connecting the same with a carriage frame and by means of which the canopy frame may be connected with or removed from the latter instantaneously.

Other objects and advantages will become apparent as the description proceeds and a more comprehensive understanding of the invention will be afforded from the following detailed specification when considered in conjunction with the accompanying drawings in which

Fig. 1 is a perspective view of a collapsible canopy frame embodying the instant invention;

Fig. 2 is a side view with sections removed showing the collapsible canopy frame in its erected position;

Fig. 3 is a side view of the canopy frame with sections removed showing the same in a partially erected position;

Fig. 4 is a side view of the canopy frame showing the same in its collapsible position, and

Fig. 5 is a side view showing an improved corner bracket by means of which the canopy frame may be attached to a supporting frame.

With reference to Fig. 1, the invention contem-

2

plates a canopy frame comprising a main bow 11 to the ends of which are bradded two corner brackets 12 and 13 by means of which the frame is attached to a supporting structure. Supported on two arms 14 and 15 of the main bow 11 are two triangularly shaped linkages each comprising respectively the links 16, 17, 18 and 19 for the arm 14, and the links 21, 22, 23 and 24 for the arm 15. To the link 16 and 21 are bradded a plurality of fabric supporting bows or ribs 25, 26, and 27 which are so attached to the links 16 and 21 as to pivot about their connecting points. Also connecting with the links 16 and 17 on the arm 14 and the links 21 and 22 on the arm 15 is a shield bow 28 which supports the forward or shield portion of the canopy. To this bow is attached a visor bow 29 which may be moved to its full line position in Fig. 1 to retract a sun visor within the shield or drop to its dotted line position to the visor carried thereon to a protecting attitude.

Inasmuch as the linkages forming the canopy locking and collapsing mechanism for both the arms 14 and 15 are identical, only one, that for the arm 14, will be described, it being understood that the operation described for the lever 19 must also be accompanied by similar operation of the lever 24.

In construction, the link 18 is pivoted to an upwardly extending arm 31 of the corner bracket 12 at a point 32. Likewise the lever 19 is pivoted to the arm 31 at the point 32, the arm 31 being positioned between the link 18 on the outside and the lever 19 on the inside, and the other end of the link 18 is pivoted at a point 33 to an arm 34 of the shield bow 28. The links 16 and 17 and the arm 34 are connected to pivot at a point 35, the parts being so arranged that the arm 34 occupies a position between the link 17 on the outside and the link 16 on the inside.

The other end of the link 17 is attached to the lever 19 at a point 36, and occupies a position between the link 18 and the lever 19. Further an attaching means 37 for fixing the link 16 to the arm 14 is such that the link may pivot thereabout. This is true for the connecting means 38, 39, and 41 and their corresponding connecting means for the collapsible linkage on the arm 15.

As may be seen in Fig. 2 when the canopy frame is locked in its erected position by moving a handle section 42 of the lever 19 and a similar section 43 of the lever 24 into contact with the respective links 18 and 23, the canopy frame is prohibited from any movement of its parts in any direction. Thus, the handles 42 and 43,

which provide means for manipulating the levers 19 and 24, also form stop means for limiting the rearward movement of these two levers to a place where the pivot point 36 and a corresponding pivot point 44 are moved past dead center. When in this position, if the bow 28 is pressed downwardly in an attempt to collapse the canopy frame, the force applied thereto will be transmitted directly through the links 18 and 23 to the corner brackets 12 and 13 and the whole frame in its erected position will pivot on its supporting structure about the points 45 and 46. Conversely, if a lifting force is applied to the bow 28 a reverse force will be effective through the same linkage to force the main bow 11 against its support and no movement of the various component parts of the canopy frame will result.

As the levers 19 and 24 are moved forwardly (clockwise in the figure), the pivot points 36 and 44 are moved forwardly out of dead center, and either a lifting force on the bow 28 or continued forward movement of these levers will collapse the frame. In either instance the bow 28 rotates rearwardly (counter-clockwise in the figure) about the points 33 and 47 and the links 17 and 22 are thrust forwardly causing the points 35 and 48 to describe arcs about the points 33 and 45 as centers until they assume positions illustrated in Fig. 3. Thereafter the shield bow 28 continues to move about the points 35 and 48 until it occupies a position above the main bow 11, as is illustrated in Fig. 4.

With reference to Fig. 4 it will be noted that rotation of the levers 19 and 24 in a counter-clockwise direction cannot be resorted to to erect the canopy since the links 17 and 22 are in dead line positions with respect to the arms of the bow 28. Accordingly, raising of the canopy is effected by movement of the bow 28 in a clockwise direction until it occupies its front forward position which will carry all of the component parts of the frame into their erected positions. The frame is then locked by forcing the handles 42 and 43, as stops, against the links 18 and 23 as previously described.

A modification of the corner brackets heretofore described is illustrated in Fig. 5. Here a bracket is shown which comprises an arm 49 by means of which it is attached to the arm of a main bow, such as 14. A second arm 51, making an obtuse angle with the arm 49, also forms a part of the bracket and the same is drilled at 52 to receive a bolt or other pivoting means for the links of the locking mechanism described above. An elongated hole 53 is drilled in the arm 51 and a slot 54 is cut therein which communicates with the hole 53. Through this slot a connecting pin for fixing the collapsible canopy to its supporting structure may be passed into the hole 53 without removal of any portion of the attaching means, such as a nut of a bolt.

While a preferred embodiment of the invention has been illustrated and described, it is possible the same may be practiced in other ways without departing from its basic concepts. Accordingly, and insofar as they fall within the scope of the appended claims any changes or modifications to which the invention is susceptible are considered to be included as if described.

What is claimed is:

1. A collapsible canopy frame comprising a main bow having a first and a second arm, a first and second mechanism supported on said arms each comprising first and second supporting links carrying a plurality of fabric supporting bows, first and second straight links connected at one end with said supporting links, first and second curved links and first and second levers pivoted for movement about points supported on said arms of said main bow, said first and second levers receiving respectively an end of said first and second straight links and the same being pivotally attached thereto at points above a point of connection between said curved links and said levers with said main bow, a shield bow connected with said supporting links and said straight links at their points of connection and arranged to pivot thereabout, said shield bow having arms with which said first and second curved links connect, and stop means carried on said first and second levers movable against said first and said second curved links to lock said shield bow in an erected position, said first and second levers being movable from their locking position to cause said shield bow to pivot about points characterized by its connection with said curved links to move the same into superposition with said main bow.

2. A collapsible canopy frame as claimed in claim 1 including a visor bow depending from said shield bow.

3. A collapsible canopy frame as claimed in claim 1 including first and second angular brackets connecting respectively with the first and second arms of said main bow for attaching said canopy frame to a supporting structure.

4. In combination with a collapsible canopy frame having a main bow and a shield bow interconnected by two straight links each pivotally connected at one end with said shield bow and at its other end with said main bow, a frame collapsing and locking mechanism supported on an arm of said main bow comprising a curved link connecting with an upright arm on said main bow in one instance and with said shield bow in a second instance, a lever having stop means thereon connecting with said upright arm and pivoted to move thereabout, and a straight link connecting with a pivot point on said shield bow in a first instance and with a pivot point attaching the same to said lever in a second instance, said last pivot point occupying a position above the pivot point of said upwardly extending arm, said lever being movable in a first instance to lock said shield bow in its erected position and movable in a second instance to cause the same to pivot about its pivot point connecting the bow with said curved link.
